UNITED STATES PATENT OFFICE.

JOHN D. O'FLYNN, OF VANCOUVER, BRITISH COLUMBIA, CANADA.

NEWSPAPER VENDER.

Application filed July 17, 1925, Serial No. 44,276, and in Canada May 9, 1925.

This invention relates to a newspaper vending machine which is designed to deliver a paper to the applicant on the presentation of the desired coin, the presence 5 of the coin enabling the purchaser to operate the machine to deliver a paper.

The invention is particularly described in the following specification, reference being made to the drawings by which it is 10 accompanied, in which:

Fig. 1 is a vertical section on the line 1—1 in Fig. 2.

Fig. 2 is a plan with the cover removed.

Fig. 3 is a detail of the means by which 15 the coin forms the connection between the external and the internal operating mechanism.

Fig. 4 is a detail of the ratchet pawl which prevents backward movement of the 20 operating shaft.

Fig. 5 is a detail of the means whereby the coin slit is closed when the magazine supply of papers is exhausted, and

Fig. 6 is a detail in perspective of the 25 paper cleats.

In these drawings 2 represents a boxlike receptacle, preferably of sheet metal, having a cover 3 over that portion of it within which the papers are stacked, which cover 30 is hinged at 4 and may be secured by a suitable lock.

In the bottom of this box 2 two endless chains 5 are spaced apart and pass around driving sprockets 6 secured on an axle 7 35 across the front of the box and around grooved sheaves 8 rotatably mounted on an axle 9 across the back.

Extending across between the upper stretches of these chains 5 is a series of 40 right angled strips 10, the front and back edges of the horizontal components of which strips, see Fig. 6, are connected to the links of the chains 5 with the upright components projecting from the forward 45 edges.

A plate 12, secured to the chains 5 extending across between them, is slidably supported on a guide rod 13, one outside each chain 5, and parallel therewith. This 50 plate 12 supports the papers in an upright position and moves forward with them as they are one by one delivered from the magazine to purchasers.

At the front of the machine the bottom 55 of the box drops down as at 14, into which drop the papers individually fall from the

chain strips 10 as they pass around the front sprockets 6. In the middle of this drop 14 a portion 15 is removed to afford the purchaser a finger hold on the paper 60 delivered and enable it to be withdrawn.

From a slit 19, adapted to receive the coin for which the machine is designed, a coin chute 18, 17 extends downward and forward to deliver radially into one of the 65 slots of a wheel 16, see Fig. 3, secured on the sprocket shaft 7. The lower length 17 of this coin chute is pivotally mounted to turn on the shaft 7 and at its connection to the upper length 18 is checked in alignment 70 with it by a bevel or overlap 23 against which it is normally held by a spring 22.

By means of a handled rod 21 projecting through the front of the casing 2 this 75 lower length 17 of the coin chute is movable as a lever to rotate the sprocket shaft 7 through an annular distance approximately equal to the pitch of the paper carrying strips 10 on the chains 5, but only when a coin of the proper size has been deposited in the slit 19, as when this coin moves down the chute into a slot of the wheel 16, it constitutes a driving connection between the lower length 17 of the chute and the sprocket shaft 7.

A ratchet wheel 33 is secured on the shaft 7 adjacent the coin wheel 16, in the teeth of which bears the end of a spring 34 to prevent backward rotation of the shaft, see 90 Fig. 4.

To prevent a coin being deposited in the slit 19 when the supply of papers in the magazine is exhausted, a shutter 25 is slideable beneath the coin slit 19, the end of which shutter is downwardly turned in the path of the upper end 26 of a lever pivoted at 27 to a bracket secured to the top of the casing 2. This lever extends below its pivot, as at 28, and its end is upturned to be engaged by the laterally turned end of 100 a small bell-crank lever 29 pivoted at 30.

The other end of this bell-crank lever projects in the path of a member 31 secured to the slide of the paper support 12; so that when the last paper has been delivered, the member 31 engages the upwardly projecting member of the bell-crank 29 and moves it to withdraw the other end from its engagement with the turned end of the lever 28, allowing that lever to be drawn back under the impulse of the spring 32 and its upper end 26 to engage the downwardly 110

turned end of the shutter 25 and move that shutter to close the aperture 19.

The end of the shaft 7 is squared as at 11 and an aperture 35, closable with a shutter on the inner side of the casing, permits a handle to be applied to the squared end whereby, when the magazine has to be recharged, the spring ratchet 34 may be lifted and the shaft 7 rotated backward for recharging with papers.

In use, the cover 3 being opened and the cash, from the previous charge of papers, removed, the aperture 35 is opened from within and a handle applied to the squared 15 end 11 of the sprocket shaft 7. The check spring 34 may then be lifted from engagement with the teeth of the ratchet wheel 33 and the shaft 7 rotated backward to carry the supporting plate 12 to the back of the 20 machine, and the paper holding strip 10 disposed on the upper stretches of the chain 5.

The handle is then removed from the shaft 7 and the aperture 35 closed, and a 25 charge of papers is arranged one on each strip 10 to rest on the horizontal portion thereof. The lower end of the lever 26, 28 is then connected to the bell-crank 29 and the shutter 25 is drawn back to open the 30 coin slit 19. The cover 3 is then closed and locked.

When a party desires a paper they drop a coin 24 in the slit 19 and it passes down the chute 18, 17 and lodges in the slot of 35 the coin wheel 16, in which position, half in the wheel and half in the chute, it forms a driving engagement between the lower section 17 of the chute and the sprocket shaft 7. The handle 21, when drawn out, will 40 thus rotate the wheel 16 through a sufficient arc to drop the front end paper off its chain strip 10 and into the depression 14 from which it may be readily removed through the slit below the front of the casing.

On release of the handle rod 21 the mechanism of the device is restored by the spring 45 22 to its normal position ready for deposit of another coin and delivery of another paper in the same manner.

When the last paper has been delivered 50 the rod 31 engages the upwardly projecting portion of the bell-crank 29 and moves that bell-crank to withdraw the other end of it from engagement with the upwardly turned 55 end of the lever 28. That lever then moves back under the impulse of its spring 32 and moves the shutter 25 to close the slit 19, so that a coin cannot be received unless there is a paper to deliver.

Having now particularly described my 60 invention, I hereby declare that what I claim as new and desire to be protected in by Letters Patent, is:

A device for vending newspapers comprising a casing having a shallow depressed 65 pocket across the front of the bottom into which the lower edges of the papers are delivered, said pocket being open at the front to expose said lower edges of the paper only, a pair of spaced endless chains passing 70 over idler pulleys and over sprockets, a driving shaft on which said sprockets are mounted and by which said chains may be moved, a series of L-shaped angled strips, the horizontal component of each of which 75 is provided with anchoring hooks for connecting the same to the respective chains, said strips adapted to receive the papers in vertical file, a follower plate secured to and between the chains and movable with the 80 same, guide rods paralleling the chains on which said follower plate is slidably mounted, all being arranged substantially as shown and described.

In testimony whereof I affix my signature. 85

JOHN D. O'FLYNN.
